CLAIM

The ornamental design for an interlockable bottle cap, as shown and described.

DESCRIPTION

FIG. 1 is a top view of an interlockable bottle cap, showing my design;

FIG. 2 is a front view thereof, the rear view being a mirror image thereof;

FIG. 3 is a right side view thereof, the left side being a mirror image thereof;

FIG. 4 is a bottom view thereof;

FIG. 5 is a top perspective view thereof;

FIG. 6 is a bottom perspective view thereof;

FIG. 7 is a close-up perspective view of a male connector portion of FIG. 5 thereof;

FIG. 8 is a close-up perspective view of a female connector portion of FIG. 6 thereof;

FIG. 9 is a top perspective view thereof, shown in a condition of use with a bottle, forming no part of the claim;

FIG. 10 is a top perspective view thereof, shown in a condition of use with other interlockable bottle caps forming no part of the claim; and,

FIG. 11 is a top view thereof.

The evenly broken lines are shown for the purpose of illustrating environmental structure and parts of the article

(Continued)

that form no part of the claim. The dot-dash broken lines represent the designations of enlargement views and form no part of the claim.
